[57] CLAIM

The ornamental design for a handrail rim for a spa, as shown and described.

DESCRIPTION

FIG. 1 is a perspective view of a first embodiment showing a handrail rim for a spa according to the design of the present invention;

FIG. 2 is a perspective view of a second embodiment showing a handrail rim for a spa according to the design of the present invention;

FIG. 3 is a perspective view of a third embodiment showing a handrail rim for a spa according to the design of the present invention;

FIG. 4 is a sectional view taken along line 4—4 of FIG. 2;

FIG. 5 is a perspective view thereof; and,

FIG. 6 is a partial front elevational view thereof.

The broken lines showing a spa are for illustrative purposes only and do not form a part of the claimed design.
